(57) **ABSTRACT**

A new and distinct variety of *Phalaenopsis* plant named
'PHALIPVLA', particularly characterized by white flowers
with greenish-yellow and white lips, a concave flower shape
in lateral view, three or more peduncles, and is propagated
by meristem tissue culture, is disclosed.

3 Drawing Sheets

1

Genus and species: *Phalaenopsis* hybrid.
Variety denomination: 'PHALIPVLA'.

BACKGROUND OF THE NEW PLANT

The present invention relates to a new and distinct cultivar of *Phalaenopsis* plant, botanically known as *Phalaenopsis* hybrid of the Orchidaceae family, commonly referred to as moth orchid, and hereinafter referred to by the variety name 'PHALIPVLA'.

The new *Phalaenopsis* plant is a product of a planned breeding program conducted by the inventor in Bleiswijk, the Netherlands. The objective of this breeding program was to create a new *Phalaenopsis* plant with few peduncles and attractive white flowers with greenish-yellow and white lips, suitable for potted plant production.

The new *Phalaenopsis* plant 'PHALIPVLA' is a result of cross-pollination made by the inventor in September 2012 in Bleiswijk, the Netherlands, of the proprietary female, or seed parent, *Phalaenopsis* hybrid '21232-01' (unpatented) with the proprietary male, or pollen parent, *Phalaenopsis* hybrid 'PHALGOWIJ' (U.S. Plant Pat. No. 30,300).

The new *Phalaenopsis* was selected by the inventor as a single plant within the progeny of the stated cross-pollination in a controlled greenhouse in Bleiswijk, the Netherlands, in July 2015. Asexual reproduction of the new *Phalaenopsis* plant by meristem tissue culture since 2016 in Bleiswijk, the Netherlands, has demonstrated that the new variety reproduces true to type with all of the characteristics, as herein described, firmly fixed and retained through successive generations.

Community Plant Variety Rights for this variety have been applied for in the European Union on Sep. 20, 2019 (Application no. 2019/2311), by Applicant who obtained the subject matter disclosed directly from the inventor. 'PHALIPVLA' has not been made publicly available or sold anywhere in the world prior to the effective filing date of this application with the exception of sales or disclosures made

2

one year or less before the effective filing date of this claimed invention by Applicant who obtained 'PHALIPVLA' directly from the inventor.

5 SUMMARY OF THE INVENTION

The following are the most outstanding and distinguishing characteristics of this new cultivar when grown under normal horticultural practices in Bleiswijk, the Netherlands, 10 and can be used to distinguish 'PHALIPVLA' as a new and distinct variety of *Phalaenopsis* plant:

- 1) White flowers with greenish-yellow and white lips;
- 2) Flower shape in lateral view is concave; and
- 3) Plant has three or more peduncles.

15 DESCRIPTION OF THE PHOTOGRAPHS

20 This new *Phalaenopsis* plant is illustrated by the accompanying photographs which show the overall plant habit including blooms and foliage of the plant; the colors shown are as true as can be reasonably obtained by conventional photographic procedures. The photographs were taken in a 25 greenhouse in Bleiswijk, the Netherlands, from 50-week-old plants in December 2020. Colors in the photographs may differ from the color values cited in the detailed botanical description, which accurately describe the actual colors of the new variety.

25 FIG. 1 shows the overall plant habit, including blooms and foliage of 'PHALIPVLA'.

30 FIG. 2 shows a close-up of a flower of 'PHALIPVLA'.

35 FIG. 3 shows an overhead view of the leaves of 'PHALIPVLA'.

DESCRIPTION OF THE NEW VARIETY

The following detailed description sets forth the distinctive characteristics of 'PHALIPVLA'. Plants of the new *Phalaenopsis* have not been observed under all possible environmental conditions. The phenotype may vary some-

what with variations in environment such as temperature, light intensity, and day length, without, however, any variance in genotype. The chart used in the identification of colors described herein is The R.H.S. Colour Chart of The Royal Horticultural Society, London, England, 2015 edition, except where general color terms of ordinary significance are used. The color values were determined under 4000-6000 lux natural light in a greenhouse in Bleiswijk, the Netherlands. Observations and measurements were made in December 2020 on flowering plants which were planted in 12-centimeter (diameter) pots. After in vitro propagation, the plants were grown in nursery trays for 20-24 weeks, followed by transplantation to 12-centimeter pots and grown in a greenhouse between 27° C. to 29° C. for 30 weeks, continued by a cooling period of 8 weeks between 18° C. to 20° C. and 12 weeks in a greenhouse of 21° C. Flowering occurs after 50 weeks in 12-centimeter pots.

Classification:

Family.—Orchidaceae.*Botanical*.—*Phalaenopsis* hybrid.*Common name*.—Moth orchid.*Variety name*.—‘PHALIPVLA’.

Parentage:

Female parent.—*Phalaenopsis* cultivar ‘21232-01’ (unpatented).*Male parent*.—*Phalaenopsis* cultivar ‘PHALGOWIJ’ (U.S. Plant Pat. No. 30,300).

Propagation:

Type.—Meristem tissue culture.

Roots:

Root description.—Greyed-green (a color in between RHS 190B and 190C) colored roots with branching lateral roots having yellow-green (RHS 144C) colored root tips.

Plant:

Crop time to flowering.—Following asexual propagation (in vitro), the rooted cuttings grow for 20-24 weeks. After transplantation into 12-cm pots, the plants are finished after 48 to 50 weeks.*Growth habit of the peduncle*.—Upright to slightly pendent with raceme inflorescence.*Height (from soil level to top of inflorescence)*.—Approximately 44.0 cm to 49.0 cm.*Width (measured from leaf tips)*.—About 23.0 cm to 26.0 cm.*Vigor*.—Strong.

Leaves:

Mature leaves.—Quantity per plant: 8 to 10 leaves are produced before flowering. Length (fully expanded): 10.0 cm to 13.0 cm. Width: 6.0 cm to 7.0 cm. Position of the broadest part of the leaf: At the middle. Shape: Oblong. Base shape: Moderately to slightly elongated. Apex: Slightly unequal obtuse. Leaf blade angle with the petiole (measured from the horizontal position): Between 10 degrees and 25 degrees. Leaf margin: Entire. Color: Upper surface: RHS 146A. Lower surface: RHS 146B. Texture (both upper and lower surfaces): Smooth. Thickness: 1.8 mm to 2.2 mm. Variegation: Absent. Venation: Pattern: Parallel. Color of the midvein: Upper surface: RHS 146A. Lower surface: RHS 146B.

Peduncle:

Quantity per plant.—2 to 4.*Number of flowers per peduncle*.—6 to 9.*Length*.—44.0 cm to 49.0 cm.*Diameter*.—5.0 mm to 6.0 mm.*Strength*.—Strong.*Aspect*.—Upright to slightly pendent.*Texture*.—Smooth.*Color*.—Yellow-green (a color in between RHS 146A and 146B).*Internode length*.—3.0 cm to 4.0 cm.

Inflorescence description:

Appearance.—Upright to slightly pendent, raceme inflorescence with bilaterally symmetrical flowers that open in succession beginning with the lowermost flower.*Number of inflorescences*.—2 to 4.*Inflorescence size*.—Height (from base to tip): 130.0 mm to 160.0 mm.*Flowering time*.—First flowers can be expected 10 to 11 months after planting in a 12-cm pot.*Flower*.—Height: 70.0 mm to 75.0 mm. Diameter: 85.0 mm to 90.0 mm. Depth of lip: 23.0 mm to 25.0 mm.*Flower longevity*.—On the plant: 11 to 13 weeks.*Flower shape*.—Concave.*Fragrance*.—Absent.*Flower bud*.—Average size: Large. Length: 25.0 mm to 27.0 mm. Width: 20.0 mm to 22.0 mm. Shape: Egg shaped. Color: Light yellow-green (a color in between RHS N144D and 145C) with a touch of diluting purplish-red (RHS N77B).*Petals*.—Arrangement: Open/free. Shape: Semi-circular. Apex: Emarginated asymmetric. Margin: Moderately undulated. Length (from base to tip): 40.0 mm to 43.0 mm. Width: 52.0 mm to 55.0 mm. Position of the broadest part of the petal: Toward the base. Color (when fully opened): Upper surface: Basic color: White (RHS NN155C). Over color: Absent. Lower surface: Basic color: White (RHS NN155C). Over color: Absent. Number of spots and stripes on the petals (upper surface): None. Color of spots and stripes on the petals (upper surface): Not applicable. Density of netting of the petals (upper surface): None. Color of the netting (upper surface): Not applicable.*Dorsal sepal*.—Shape: Elliptic. Apex: Emarginated symmetric. Margin: Entire. Length (from base to tip): 40.0 mm to 43.0 mm. Width: 29.0 mm to 32.0 mm. Position of the broadest part of the dorsal sepals: At the middle. Color (when fully opened): Upper surface: Basic color: White (RHS NN155C). Over color: Absent. Lower surface: Basic color: White (RHS NN155C). Over color: Light yellow-green (RHS 145C) with a touch of very light purple (RHS 76B). Number of spots and stripes on the dorsal sepals (upper surface): None. Color of spots and stripes on the dorsal sepals (upper surface): Not applicable. Density of netting of the dorsal sepals (upper surface): None. Color of the netting: Not applicable.*Lateral sepals*.—Shape: Ovate. Apex: Obtuse asymmetric. Margin: Entire. Length (from base to tip): 43.0 mm to 45.0 mm. Width: 27.0 mm to 29.0 mm. Position of the broadest part of the lateral sepals: Toward the base. Color (when fully opened): Upper

surface: Basic color: White (RHS NN155C). Over color: Touch of light yellow-green (RHS 145C) at the base. Lower surface: Basic color: White (RHS NN155C). Over color: Light yellow-green (RHS 145C) at the base and hint of light purple midvein (RHS 76A) toward the tip. Number of spots and stripes on the lateral sepals (upper surface): None. Color of spots and stripes on the lateral sepals (upper surface): Not applicable. Density of netting of the lateral sepals (upper surface): None. Color of the netting (upper surface): Not applicable.

Labellum (lip).—Whiskers: Present. Length of whiskers: 16.0 mm to 18.0 mm. Color of whiskers: White (RHS NN155C) with light greenish-yellow tips (RHS 1C). Pubescence on the lip: Absent.

Lateral lobe.—Shape: Type V (as described in the International Union for the Protection of New Varieties of Plants (UPOV) Test Guidelines for *Phalaenopsis*); spatulate Margin: Undulated (widely wavy). Length: 21.0 mm to 23.0 mm. Width: 17.0 mm to 19.0 mm. Color: Upper surface: Touch of light yellow-green (RHS 4D); striped (RHS N77B and 183B) at the base; greenish-yellow (RHS 151B) at one margin toward the base; white (RHS NN155C) toward the other margin and the tip. Lower surface: Greenish (RHS 151B) on one margin toward the base and touch of diluting pink (RHS 185D) on the other side; white (RHS NN155C) toward the other margin. Number of spots and stripes on the lateral lobe: Medium stripes. Color of spots and stripes on the lateral lobe: RHS N77B and 183B. Density of netting of the lateral lobe: None. Color of the netting: None.

Apical lobe.—Shape: Triangular. Margin: Entire. Length: 23.0 mm to 25.0 mm. Width: 23.0 mm to 25.0 mm. Color: Upper surface: Reddish-orange margin (RHS 176C) at the base; greenish-yellow wings (RHS 154B) and white (RHS NN155C) toward whiskers. Lower surface: Reddish-orange margin (RHS 176C) at the base; diluting greenish-yellow wings (RHS 154C); white (RHS NN155C) toward whiskers. Number of spots and stripes on the apical lobe: None. Color of spots and stripes on the apical lobe: None. Density of netting of the apical lobe: None. Color of the netting: None. Bump and ridge: Present.

Callus.—Average size: Medium. Height: 0.6 cm to 0.7 cm. Length: 0.6 cm to 0.7 cm. Width: 0.5 cm to 0.6

cm. Color: Greenish-yellow (RHS 3A) and light greenish-yellow (RHS 3C) on sides; dotted (RHS 176B).

Reproductive organs:

Column.—Length: 7.0 mm to 9.0 mm. Diameter: 5.8 mm to 6.3 mm. Color: White (RHS NN155C).

Pollinia.—Quantity: 2. Diameter: 0.8 mm to 1.0 mm. Color: Orange (RHS 24A).

Ovary.—Length: 14.0 mm to 16.0 mm. Diameter: 2.1 mm to 2.4 mm.

Pedicel.—Length: 36.0 mm to 40.0 mm. Diameter: 2.6 mm to 3.0 mm. Texture: Smooth. Color: Yellow-green (RHS 144B) at the base and very light yellow-green (RHS 144D) toward the flower.

Disease, pest, and stress resistance: No specific resistance or susceptibility observed to pathogens and pests common to *Phalaenopsis* to date.

Fruit and seeds: Fruit and seed development has not been observed on plants of the new *Phalaenopsis* to date.

COMPARISON WITH PARENTAL LINES AND MOST SIMILAR VARIETIES

‘PHALIPVLA’ differs from the female parent plant ‘21232-01’ (unpatented), in that ‘PHALIPVLA’ has white whiskers with light greenish-yellow tips, whereas ‘21232-01’ has white whiskers. Additionally, ‘PHALIPVLA’ has longer whiskers than ‘21232-01’.

‘PHALIPVLA’ differs from the male parent plant ‘PHALGOWIJ’ (U.S. Plant Pat. No. 30,300) in that ‘PHALIPVLA’ has a weak curvature of the lateral lobe, whereas ‘PHALGOWIJ’ has a medium curvature of the lateral lobe. Additionally, ‘PHALIPVLA’ has shorter whiskers than ‘PHALGOWIJ’.

‘PHALIPVLA’ is most similar to the commercial *Phalaenopsis* plants named ‘PHALGONDAL’ (U.S. Plant Pat. No. 29,908) and ‘PHALFUBNE’ (U.S. Plant Pat. No. 30,395). ‘PHALIPVLA’ differs from the commercial variety ‘PHALGONDAL’ in that ‘PHALIPVLA’ has larger flowers and shorter whiskers than ‘PHALGONDAL’.

‘PHALIPVLA’ differs from the commercial variety ‘PHALFUBNE’ in that ‘PHALIPVLA’ has emarginated dorsal sepal apexes, whereas ‘PHALFUBNE’ has obtuse dorsal sepal apexes. Additionally, ‘PHALIPVLA’ has smaller flowers and shorter whiskers than ‘PHALFUBNE’.

I claim:

1. A new and distinct variety of *Phalaenopsis* plant named ‘PHALIPVLA’, substantially as described and illustrated herein.
